UNITED STATES PATENT OFFICE.

HERMAN JACOBSON, OF BROOKLYN, NEW YORK.

DESIGN FOR A TEXTILE FABRIC.

No. 39,239.

Specification for Design.

Patented March 31, 1908.

Application filed February 6, 1908. Serial No. 414,656. Term of patent 3½ years.

To all whom it may concern:

Be it known that I, HERMAN JACOBSON, a citizen of the United States, residing in Brooklyn, New York, N. Y., and whose post-office address is Brooklyn, New York, have invented a new, original, and ornamental Design for Textile Fabrics, of which the following is a specification, reference being had to the accompanying drawing, forming a part thereof.

The drawing represents a plan view of a piece of the fabric.

I claim:

The ornamental design for a textile fabric, as shown.

HERMAN JACOBSON.
